UNITED STATES PATENT OFFICE.

OTWELL FRAZER, OF CYNTHIANA, KENTUCKY.

RECORD-KEEPING DEVICE

1,243,726.

Specification of Letters Patent. Patented Oct. 23, 1917.

Application filed October 13, 1913. Serial No. 794,990.

To all whom it may concern:

Be it known that I, OTWELL FRAZER, a citizen of the United States, residing at Cynthiana, in the county of Harrison and 5 State of Kentucky, have invented certain new and useful Improvements in Record-Keeping Devices, of which the following is a specification.

This invention relates to improvements in 10 record keeping devices, and more particularly to a combined warehouse record and checking form designed to save time and labor in the entry of warehouse transactions as well as to prevent the possibilities of 15 errors arising in checking up the accounts of the purchasers as well as of the manager of the warehouse. As such, my invention relates particularly to the provision of certain business forms useful in connection with 20 transactions of tobacco warehouse companies where loose leaf tobacco is received to be sold in the warehouse and from there delivered to the purchasers.

The present system of entering the various items of account connected with the sale and delivery of tobacco from tobacco warehouses is open to the objection of entailing unnecessary expense and loss of time, and further, said system does not prevent errors 25 in the entry and transcription of the various items of account and in charging them up against any particular purchaser. In such transactions it is customary for the planter of tobacco or dealer in tobacco to 30 deliver quantities of tobacco in bulk on wagons or cars to a tobacco warehouse where they are divided into different lots or baskets bearing identifying serial numbers to be sold to the highest bidder in the warehouse. 35 At any one time a sale of the tobacco in the warehouse belonging to any particular planter or dealer may embrace several lots, and many different purchasers may be entitled to a delivery of the tobacco sold. Therefore, it is important, in making a record of 40 any such transaction, to identify the particular sale at which certain purchasers have obligated themselves to pay the amount charged up against them as established by 45 the various warehouse records. Furthermore, it often happens that a planter or dealer is unwilling to consummate a sale,

for some particular reason, in which case a reduction in the amount of money due and payable by, and also in the quantity of 55 tobacco to be delivered to a purchaser must be made in order to avoid any error in charging up accounts, and in the listing of baskets of tobacco. The nature and purposes of my invention will be understood 60 when taken in connection with the accompanying drawings and specification in which—

Figure 1 is a face view of a warehouse card made out in triplicate for a purpose to 65 be described,

Fig. 2 is an end elevation of said card, in folded position,

Fig. 3 is a face view of another of said cards made out in triplicate, 70

Fig. 4 is a face view of a sheet of a scale or sales book to be described,

Fig. 5 is a face view of the manager's receipt and rejection slip to be described,

Fig. 6 is the manager's receipt and the 75 rejection slip having marked thereon different entries for a purpose to be described, and

Fig. 7 is a sheet of a check-out book to be 80 described.

The most important part of my invention consists in providing a warehouse business form called a manager's receipt and rejection slip. This is the only record which requires the stamping of a date and from 85 which all the transcriptions are made in the various books of accounts, cards, and receipts incident to warehouse transactions. Referring particularly to Figs. 5 and 6 this form is clearly shown. At the top of the 90 slip 1 is written or printed the name of the warehouse company as at 2, and immediately under said name is written or printed the words "Manager's receipt and rejection slip" as at 3. It will be understood that 95 numerous other inscriptions may appear on said slip as may be found necessary in practice, but it will be necessary, in carrying out the purposes of my invention, to mark or inscribe the following headings:—At 4 is designated the term "Per" followed by a fine, 5 refers to the term "Date", 6 designates "Sales made for" followed by a line, 7 upon which will preferably be written the

post-office address of the customer, as this is the only instance where the address is kept. Immediately under the above inscriptions are written or printed a series of vertically spaced lines as at 8 which intersect with the spaced apart vertical lines 9 whereby suitable columns 10 are formed which are designated respectively by the following printed or written headings,—“Basket No.” and 10 “Pounds”. There may also be printed or marked upon the face of said columns the head “Brought forward”. 11 designates the horizontal column in which the totals may be designated, and 12 designates columns in 15 which are respectively marked or printed the headings “Baskets weight pounds”, “Sales No.”, “Lot No.” Beneath the columns 12 are to be marked or printed substantially at the center of the slip the following headings, arranged one beneath the other,—“No. lbs. offered”, “No. lbs. removed”, “No. lbs. rejected”, “No. lbs. sold”, and lastly “O. K.” At the left of said headings are alining columns 14 which are particularized by the heading “Baskets”. The entries to be made are first written upon the manager's receipt and rejection slip then transcribed to the warehouse cards, which, as illustrated, are made out in triplicate, 30 there being one card for the buyer, another for the factory and a third is designed as a warehouse receipt. Figs. 2 and 3 show the form of the warehouse card, and differ only in designating the nature of the sale recorded. It is essential to my invention that the following headings shall be marked or printed uniformly and consistently upon each of the detachable coupons 14' of which the warehouse card is composed, in the particular order to be described. At the right hand corner of each coupon 14', is to be preferably printed the heading “Sale No.” followed by a line, immediately underneath said heading will appear the name of the 45 warehouse company, as at 16, and underneath said last-named heading, at the left hand side and spaced from the end of each coupon will appear one underneath the other and followed by suitable lines the following 50 headings as at 18:—“No.”, “Planter”, “Price”, “Buyer”, and to the right of said last-named headings will appear the heading “Lot No.” followed by a line, and the heading “Lbs.” preceded by a line. There 55 may be marked or printed immediately to the left of the headings 18 vertical lines 19, and marked or printed parallel to said lines 19 on the several coupons 14' will be the headings “Buyer's coupon”, “Factory coupon”, and “Warehouse receipt”.

In carrying out my invention I propose to effect a change in the present system of selling loose leaf tobacco in warehouses with the distinct object in view of avoiding any pos-

sible loss of any basket after being received 65 or placed on the floor, also errors and loss of time in the entry of accounts in warehouse transactions and in the delivery of baskets of tobacco to the purchasers. There will be displayed by a suitable placard or sign, at 70 one end of the warehouse prominently and distinctly preferably in bold type the number of the sale, said number being so designated upon said sign or placard. The purpose of displaying this sign of the sale number is to enable the receiving clerk to write the number of sale on each coupon designated “Buyer's coupon”, “Factory coupon” and “Warehouse receipt,” respectively, of the warehouse card 14', together with the 75 names of the parties from whom the tobacco is received. When the cards have thus been marked, the same entries are later made upon the manager's receipt or rejection slip shown in Fig. 7, then the tobacco is sent to 80 the scale room, where the lot number and the weight of each basket of tobacco is put on each coupon of the warehouse card, and the weight entry is likewise made upon the manager's receipt opposite the number of 85 the basket, so that the manager's receipt and rejection slip may then show the number of baskets of tobacco and the pounds offered for sale by a planter, this information having been copied upon said manager's receipt 90 from the factory coupon. If a party is not willing to sell all of his tobacco, then a rejection is necessary, which makes it necessary for the rejection clerk to take the manager's receipt and mark out with a pencil or pen 95 the number of each basket the seller wishes to withdraw; he also stamps or perforates the warehouse card 14' indicating the basket number withdrawn from sale. The planter will receive a warehouse receipt for every 100 basket of tobacco he brings to the warehouse and the information thereon should tally exactly with the information on the manager's receipt or rejection slip, so that he may know at any time just what amount is due him by 105 his receipts. It sometimes happens when a customer's tobacco is unloaded, the baskets, for some reasons, cannot be weighed for several hours. The manager's receipt having the number of each basket makes it impossible to appropriate another's tobacco by changing cards. It is the only safeguard for the farmer between the time he unloads his wagon until the tobacco is weighed in 110 the scale room as no one can steal his tobacco after the receiving clerk places the number of baskets or basket on his manager's receipt. 115

In Fig. 4 is illustrated a single sheet of the sale or sale book designated 20 which in addition to being provided with the horizontal lines 21 are provided with the vertical lines 22 whereby a series of columns 23 are formed which are particularized by the 120 125

headings, extending from left to right, as follows as designated at 24,—“Seller,” “Basket,” “Lot No.,” “Buyer,” “Weight,” “Price,” “Total.” It is particularly to be noticed that, in this sale book, it is important to enter under the heading “Seller,” the name of preferably the same planter whose various baskets of tobacco under varying lot numbers are offered for sale in the warehouse. As in general use, the scale book, on which all tobacco is entered that comes into a warehouse, has each line numbered as designated as at 25, said numbers starting from zero and running to 99, and when the 99th mark is passed, there will be added at the top of the column the figure 1 or 2 with the addition of the necessary digits so as to designate what other numbers are being reached. Each sale book holds about 2550 lines, so it will be seen that when the second and other sale books are necessary, generally in about one week, it will be necessary to carry the serial lot numbers on to each book which in turn would make it necessary, as the transactions progressed well into the season, to place on each warehouse card a separate serial lot number aggregating into the thousands. Bearing this in mind, it will be evident that by employing my system of entry there will be saved the repetition of the serial lot numbers which would never run higher than 2550, because of the conspicuous display while a sale is going on of the sale number, and as clearly shown in the upper right hand corner of the sheet of the sale book shown in Fig. 4, at 26, there is stamped or otherwise designated the sale number, so that, the various warehouse cards can be assembled having the same sale number written thereon, by simply referring to the sale book where each lot number follows in consecutive order and refers to the basket of tobacco sold which belongs to a single planter or dealer. It will be observed that in accordance with the principle above stated, there is printed on the upper left hand corner of the scale sheet number 24, which goes with each of the numbers 75, 76, etc., arranged in an ascending scale, thus dispensing with repeating this in front of every number. Thus it will be seen I dispense with the necessity of dating each warehouse card three times as all the warehouses are now doing, because a record is kept on the outside of the sale book of the date on which any sale designated by its number took place, and therefore every ticket marked with this serial number can be recognized as representing tobacco either sold or rejected on that date. The manager's receipt and the rejection slip is returned to the warehouse managers at the time they issue the checks for the tobacco received from any particular planter or dealer and this slip

kept by the warehouse shows the entire transaction and makes it impossible to lose a basket of tobacco.

To illustrate the manner of checking up the various sales of tobacco taking place in the warehouse the following example may be used whereby the following original entries may be traced throughout the various stages of the receipt, sale, and delivery of the tobacco belonging to any given planter or dealer say James Linehan. Suppose that the tobacco offered by said James Linehan receives the sale number 20. After the tobacco has been sent to the scale room the following entries will be made upon each coupon of the warehouse cards 14, assuming that these entries represent the tobacco actually sold. Referring to Fig. 3 it will be seen that the sale number is designated 20. The basket number 106, the planter or dealer James Linehan, price 17, the buyer Gordan, lot number 2475 and the number of pounds 240. Referring to Fig. 5 it will be seen that there is entered after the heading “Sale No.” 20, and the lot number is designated 2474, and while this lot number does not agree with the lot number 2475 two transactions are accounted for on slip 1, because said slip, on its face, refers to another and rejected transaction, namely, because, as numeral 29 points out, a line which will be preferably blue-penciled, is drawn across the basket number 410 and the pound number 205 which are marked immediately above the basket number 106 and pound number 240 referring to the entries on the warehouse cards 14 referred to above. The warehouse men will understand from this that a rejection card 14' as shown in Fig. 1 has been made out designated by the same sale number 20 to which he will refer for further particulars, and referring to Fig. 1 these particulars appear and they are as follows:—these particulars are lot number 2474, basket number 410, planter James Linehan, price 13, buyer Gordan, pounds 205, said particulars being uniformly and consistently written upon each of the coupons of said warehouse card. Referring to Fig. 5 there will be entered on the line opposite the designation of baskets, the price, and the number 445 is placed after the number of pounds offered because this is the total obtained as designated on the face of the slip 1 by adding the number of pounds rejected, namely, 205 and the number of pounds sold, 240, together. The number 205 is therefore placed after the heading “No. lbs. rejected” and the number 240 placed after the heading “No. of lbs. sold,” and under the heading “Baskets” opposite the heading “No. lbs. offered” is written the numeral 2, after the heading “No. lbs. rejected” numeral 1, and after the heading

"No. lbs. sold" the numeral 1. It will also be understood that this slip will be suitably dated, that the name James Linehan will be written after the heading "Sale made 5 for," that the name and address of the planter or dealer is placed after the heading "Address." The warehouse cards 14' when filled out will be placed in the baskets of tobacco of the planter or dealer 10 for whom the sale shall have been made, and to facilitate the identification of the various lot numbers as the tobacco belonging to one single planter or dealer reference may be made directly to the sale book, 15 where, for example, the first column will show that a warehouse card is to be placed in the basket of tobacco belonging to James Linehan, basket No. 106, lot No. 2475, weight 240, sale No. 20. By this sale book 20 it will be obvious that the next time lot No. 2475 appears it will be in connection with some other sale number, thus avoiding the repetition of lot numbers or making it necessary to carry the lot serial for an entire 25 season starting at number 1 and going on, one number higher and higher with each basket offered.

Finally in order to maintain the verification system complete up to the time the 30 baskets of tobacco are to be delivered to the purchaser, I provide, as shown in Fig. 7, a check-out book which is devoted to the name J. R. Blanks & Co., as a single page of which is illustrated, which is designated 35 30. This slip in addition to being provided with the usual horizontal lines 31 is provided with the vertically spaced apart lines 32 whereby columns 33 are formed, which are particularized by the various headings, 40 "Sale No.", "Basket No.", "Lot No.", "Price", "Pounds", and upon the horizontal line 34 is adapted to be written the name of the purchaser to whom the delivery of the tobacco is to be made. The check-out book 45 is kept by the out-check clerk, and every pound of tobacco, as shown in the manager's receipts in any certain sale, is either purchased by some buyer or is rejected by him. If purchased, the same must be 50 checked out by the clerk and the number of pounds checked out on any sale to a buyer must be the exact number of pounds with which said buyer is charged by the warehouse card and by the sale book, from which 55 cards the names of the purchasers are taken and transferred to the check-out book. Thus, on the above sale number 20 designated on the check-out slip or sheet illustrated in Fig. 7, refers to Basket No. 106, also designated in Fig. 7, and now referring to Fig. 60 4, it will be seen that E. Gordon to whom Basket 106 designated on Fig. 4 relates purchased 240 pounds of tobacco, the out-check clerk expressly lists on this book the basket

as shown by the above columns, this basket 65 being listed on this book as it is loaded on the wagon to be delivered to E. Gordon. The out-check clerk takes from each basket the part of the card 14' marked warehouse receipt as the tobacco is being loaded on the delivery wagon of the purchasers and from this card the entry is made on the out-check book or sheet. If the out-check clerk's totals amount to the same number of pounds as purchased, then no error has 70 been made and the buyer must pay for 2210 pounds of tobacco as by the statement. When a basket of tobacco is withdrawn 75 from sale because of the price offered or for any reason, the warehouse card 14', designating the transaction referring to that particular basket, is folded in the manner shown in Fig. 2, and is punched as at 80 35 with the perforated words "Rejected" together with the date of said rejection after 85 which the several coupons are separated and distributed to their proper sources. The cards may be marked otherwise other than by perforating them but a perforating punch will insure the exact information as 90 to rejection and date on each coupon.

From the above description it will be seen that I have provided a verification system comprising a combined checking form and warehouse record, and I do not mean to limit myself to the exact particulars herein disclosed, but claim all variations falling within the purview of the appended claims.

What I claim to be new and desire to 100 procure by Letters Patent is:—

1. A business record consisting of a warehouse card, a manager's receipt and rejection slip, and a scale tablet, said card having certain printed data thereon and an identifying number, said slip being designated 105 with the same scale as said card and having the same printed matter thereon as the latter, said slip having additional designations qualifying the transactions entered on said card said scale tablet being also designated with said scale number, and said printed matter, and adapted to refer to many transactions.

2. A device of the kind described comprising a warehouse card composed of detachable coupons, three in number, two of said coupons being buyer's and factory coupons, and the third a warehouse receipt, each of said coupons bearing one and the same sale number and the other entries, a manager's receipt and rejection slip upon which the same entries as upon said coupons are written, said slip being also designated by the same sale number, said slip alone being dated.

3. A business record consisting of coupons, similar printed designations appearing on said coupons, and relating to a par-

ticular sale of goods arranged in lots, said coupons having one and the same sale number but different lot numbers, and referring to one buyer, and a slip receiving the combined data of all of said coupons, and bearing the same sale number.

4. A business record consisting of coupons and a verification warehouse slip adapted to record goods sold in lots and at 10 one single sale, said coupons bearing the same sale number but different lot numbers, said coupons consisting of two series, the first series comprising records of goods sold and the other series, records of goods with- 15 drawn from sale but offered by the seller, said verification warehouse slip referring to the seller's entire sale transaction, having the same printed sale number as said coupons, and having direct reference to the contents 20 of all of said coupons, whereby the actual number of goods sold may be recorded.

5. A business record embodying the combined features of a set of coupons, an original entry sheet, and a seller's memorandum 25 sheet, said coupons, original entry sheet, and seller's memorandum sheet, all having a uniform sale number printed thereon, said coupons having items referring to the sale of articles in lots, the items on said coupons 30 being transcribed upon said original entry sheet, and the data on a plurality of original entry sheets relating to one and the same seller being transcribed on the seller's memorandum sheet.

35 6. A warehouse record consisting of printed forms designed to receive data relating to goods received at a warehouse, offered for sale and actually sold, said printed forms including coupons recording the 40 goods offered for sale by a particular seller to a particular buyer, all of said coupons having a uniform sale number printed thereon, said printed forms also including a warehouse slip having the same sale number thereon and receiving data under a particular date recording the actual goods sold by the warehouse for the seller from the 45 total goods offered.

7. A warehouse record consisting of printed forms, certain of said printed forms having data referring to goods offered for sale and identifying the seller and the buyer by name and by a specific lot number, and having a self-identifying sale number, and 50 other of said printed forms having additional data referring to a seller by name and to a buyer by lot number, and having the sale number identifying the sale, and another printed form having data referring to 55 one particular sale by its identifying sale number, to all buyers at this sale by name, and to the printed forms relating to buyers by their identifying lot numbers.

8. A warehouse business record consisting

of printed forms for seller, buyer, and warehouse, certain of said printed forms being coupons designated separately for seller, buyer, and warehouse, and having similar data printed thereon and a uniform sale number, the similar data of each coupon referring to goods offered for sale by a particular seller to a particular buyer and other 70 of said printed forms consisting of a warehouse receipt and rejection slip having a sale number corresponding with the sale 75 number of certain coupons and checking up the unsold goods referred to in the latter coupons.

9. A warehouse verification record consisting of a plurality of cross-reference 80 tablets, one of said tablets being placed together with the article to be sold and having data referring thereto, said tablet being provided with an identifying sale number, another tablet being kept by the warehouse 85 to show qualifications bearing upon the data recorded in said first-named tablet, said second tablet being alone dated and having the same sale number as said first tablet, said first tablet having designations where- 90 by to call attention to said second tablet.

10. A warehouse verification record consisting of a plurality of cross-reference tablets, one of said tablets consisting of a 95 series of coupons arranged in triplicate, one designatedly intended for seller, one for buyer, and one for warehouse, another tablet having a common sale number with each series of coupons, said coupons having data relating to articles sold by numbered lots, 100 in numbered baskets, said second tablet having data in common with said coupons and additional matter designed to qualify said data, the warehouse coupon designed to be placed in a numbered basket to check up de- 105 livery to the buyer.

11. A business record consisting of a sales tablet, said sales tablet having inscribed thereon particulars relating to goods offered for warehouse sale in baskets, said particulars relating to basket number, basket weight, lot number, said table being designated by a specified sale number, and by the name of a particular seller, a second tablet consisting of coupons in triplicate, 110 said coupons having similar data, consisting of all the particulars and designations on said first tablet but connected with a single basket and a single designated buyer, said sales tablet totaling all the baskets of 115 goods sold and referred to in a plurality of goods sold and referred to in a plurality of said triplicate coupons.

12. A business record consisting of a sales tablet, a warehouse slip, said warehouse slip containing data relating to the receipt of a basket of goods particularized by basket number, basket weight, and lot number, and identified with the name of a specified seller 125

and a specified sale number, a tablet having triplicate coupons and receiving the same particularized data and identifications on said slip and in addition the name of a specified buyer, said triplicate coupons being designatedly intended for seller, buyer, and warehouse, said slip receiving entries transcribed from a plurality of said coupon

tablets, and referring to them by basket numbers and by a single lot number.

In testimony whereof I affix my signature in presence of two witnesses.
